CLOTHESLINE HOLDER

Albert H. Endsor, Montville, N. J.

Application August 23, 1932. Serial No. 630,100

1 Claim. (Cl. 24—134)

This invention relates to clothes line holders and it has for one of its objects the provision of a simple, inexpensive and efficient device of the character mentioned and also a holder which 5 may be further employed to move a clothes line.

The invention will be fully and comprehensively understood from a consideration of the following detailed description when read in connection with the accompanying drawing which forms part 10 of the application with the understanding, however, that the improvement is capable of extended application and is not confined to the exact showing of the drawing nor to the precise construction described and, therefore, such changes 15 and modifications may be made therefrom as do not affect the spirit of the invention nor exceed the scope thereof as expressed in the appended claim.

In the drawing:

20 Fig. 1 is an elevational view, partly in section, of the device of my invention showing it mounted on a clothes line and attached to the clothes line pulley with a support for the latter, the device or holder being shown in this view as in 25 a holding or locked position.

Fig. 2 is an elevational view, partly in section, of the same device as shown in Fig. 1 but shows the same in open position; and

Fig. 3 is a section taken on line 3—3 of Fig. 2.

30 Referring to the drawing for a more detailed description thereof, the numeral 5 indicates a channel to the sides of which are secured upright members 6 between which is disposed and to which is pivoted the shank 7 of a handle 8. The

handle carries a member 9 having a convex lower surface provided with teeth 10. Said member 9 may be locked so that the line 11 is held tightly between it and the channel, as shown in Fig. 1, or it may be moved so as to permit the line to 60 pass freely between it and the channel, as shown in Fig. 2. Swivelly secured to the top of the handle is a hook 12 adapted to engage a link 13 which is swivelly mounted in an eyelet 14 integral with the clothes line pulley 15, which is supported by 65 a hook 16 screwed into a support 17.

It is obvious that the connection of the handle to the pulley is effective to hold the device in locked position gripping the line and to hold the line at any desired position. When the hook 12 70 is disengaged from the link 13 the device may be employed to move the line to any desired position, this being accomplished by pulling on the device when in a locked position, then unlocking it, then advancing it in the unlocked position, and 75 then moving it to locked position and again pulling it, the line thus being moved in successive steps to the desired position.

What is claimed as new is:

A clothes line fastener comprising a channel, a 80 convex, toothed member pivotally mounted relative to said channel and movable to hold a line tight between it and the channel or to allow the line to pass therebetween a handle extending from said convex toothed member, in combination 85 with a clothes line pulley and releasable means for securing said handle to the pulley.
